UNITED STATES PATENT OFFICE

LEWIS ALEXANDER, OF CLINTON, ILLINOIS

RAILROAD CROSSING

Application filed November 9, 1928. Serial No. 318,148.

This invention relates to railroad crossings.

Generally stated, the object of the invention is to provide a novel and improved construction that will eliminate or tend to eliminate, the jolting and jarring and bumping of the wheels as they pass over the joints between the different parts of the crossing, thereby to not only save wear and tear on the crossing construction itself, but also to eliminate more or less wear and tear on the rolling stock as well.

It is also an object to provide certain details and features of construction and combinations tending to increase the general efficiency and the desirability of a railroad crossing of this particular character.

To the foregoing and other useful ends, the invention consists in the matters hereinafter set forth and claimed, and shown in the accompanying drawings, in which,—

Fig. 1 is a plan of a railroad crossing involving the principles of the invention.

Fig. 2 is a vertical section on line 2—2 in Fig. 1.

Fig. 3 is an enlarged vertical section on line 3—3 in Fig. 1, showing the parts in normal position.

Fig. 4 is a view similar to Fig. 3, but showing the parts in the relative positions assumed thereby when the car wheels are passing over the crossing.

Fig. 5 is an enlarged detail section on line 5—5 in Fig. 1.

Fig. 6 is an enlarged detail section on line 6—6 in Fig. 1.

Fig. 7 is a perspective of one of the parts of the railroad crossing.

Fig. 8 is a similar view of another part of the construction shown and described.

As thus illustrated, the invention comprises four pairs of rail sections 1, 1, 2, 2, 3, 3, and 4, 4, arranged to provide a right angle track crossing, these rail sections being ordinary steel rails brought tightly together to form right angles or corners 5 at their junctions, as shown. The guard bars 6 are disposed inside of the rail sections, 1, 1 and 3, 3, as shown, and are provided with tapered portions 7, 7 and notches 8, 8, as shown. Similar

guard bars 9, 9 are disposed inside of the rail sections 2, 2 and 4, 4, as shown, these guard bars having tapered portions 10, 10 and notches 11, 11, as shown. The bars 6, 6 are yieldingly held against the inner sides of the rails by the coiled springs 12 on the bolts 13, which latter are anchored at one end to the rails and provided at their other ends with washers and nuts 14, whereby these springs are compressed by movement of the bars away from the rails. Similar springs 15 and similar bolts 16 hold the bars 9, 9 normally against the inner sides of the rails 2, 2 and 4, 4, as shown. Four stationary blocks 17 are disposed in position as shown, between the rails, with their beveled faces opposite the bevels of the tapered portions 7, 7 and 10, 10, in the manner illustrated, with slight spaces between the beveled surfaces at the eight points or places shown.

With this construction, car wheels in order to cross from the rails 1, 1 to the rails 3, 3 will cause inward movement of the guard bars 6, as the flanges of the wheels enter between these bars and the rails, as shown in Fig. 4 of the drawings, and the wheels will

travel smoothly from the rails 1, 1 on to the portions 10, 10 of the bars 9, 9, and over the adjacent blocks 17 and on to the rails 3, 3 without having crossed any open or rough joints that will cause any perceptible bumping or jolting of the wheels while traveling across the crossing construction. In a similar way, car wheels passing from the rails 2, 2 on to the rails 4, 4 will force the bars 9, 9 toward each other, as the flanges enter between these bars and the rails, and the wheels will then travel smoothly on to the portions 7, 7 of the bars 6, 6, and over the adjacent blocks 17, on to the rails 4, 4, without any perceptible, or at least with no very perceptible, jolting or

jarring of the wheels on the different parts of the crossing. The flanges of the wheels passing from the rails 1, 1 to the rails 3, 3 will travel through the notches 11, 11, while the flanges of wheels passing from rails 2, 2 to rails 4, 4 will pass through the notches 8, 8, in a manner that will be readily understood. As in their normal positions, the parts of the crossing are all tightly together, where the

wheels travel thereon, except between the beveled faces of the parts 7, 7, 10, 10 and 17, there will practically never be a time when the tread of a wheel will be required to jump 5 across an open joint between any parts of the crossing, but, to the contrary, will always travel over a tight joint without any perceptible, or at least any very perceptible, jarring or jolting. When the wheels travel 10 over the points of the tapered portions 10, 10, it will be understood that the treads of the wheels are broad enough to prevent any jolting or jarring at these points, because of the oblique joint formed by the beveled faces referred to. In other words, the joints at these 15 points 18, 18 and 19, 19 are oblique and are not at right angles to the direction of travel of the treads of the wheels, and hence there is no jolting or jarring at these points, 20 which would be otherwise if these joints were open joints extending at right angles to the rails or to the path of travel of the treads of the wheels. There are no flange receiving notches or gaps formed in the rails, in the 25 path of travel of the treads of the wheels, the only notches to receive wheel flanges being the notches 8, 8, and 11, 11, but these notches are not in the paths of travel of the treads of the wheels, and consequently such notches 30 are not productive of any jolting or jarring as the wheels travel across the construction forming the crossing. Of course, the guard bars are forced away from the inner sides of the rails, by the flanges of the wheels, but this does not affect the close contact of the 35 other guard bars with their rails, so that normally closed joints are possible between the inner sides of the guard bars and the inner sides of the rails, in the path of the treads of the wheels, whether crossing in one direction or the other. When the wheels are traveling from the rails 1, 1 to the rails 3, 3, it 40 will be seen that the joints between the ends of the rails 1, 1 and the inner side of the adjacent bar 9 are closed, and, similarly, at such time the joints between the other bar 9 and the adjacent ends of the rails 3, 3 are closed, thus providing practically a continuous and unbroken rail tread surface from 45 the rails 1, 1 to the rails 3, 3 for the wheels to travel upon. Similarly, if the wheels are traveling from the rails 2, 2 to the rails 4, 4, it will be seen that at such time the joints between the inner sides of the bars 6, 6 and the 50 inner sides of the rails 1, 1 and 3, 3 are closed, so that again the wheels travel smoothly without jolting or jarring. In other words, automatic or self-closing flange gaps are provided in the tread paths of the crossing, which gaps 55 are normally closed, but which are so arranged that one set of gaps will be opened by the flanges of the wheels traveling in one direction, without opening the flange gaps for wheels traveling in a direction at right angles 60 thereto, whereby the only gaps that are ever 65

open are those which necessarily open to receive the flanges of the wheels, the other set of gaps, whichever it may be, remaining closed and undisturbed, whereby all wheel treads travel on the treads of the crossing 70 construction without encountering any open gaps.

Thus the movable wheel supporting elements 10 project between the bars 6 and the blocks 17, while the similar elements 7 project between the bars 9 and the blocks 17, each of these wedge shaped movable elements projecting from its bar into a wedge shaped space formed between another bar and one of the stationary blocks. In this way, while the 80 wheels are traveling over the crossing, the wedge shaped movable elements are embraced between the wheel flanges inside and the blocks 17 outside, and in this way said blocks are in position to resist any outward distortion of the tapered movable elements, by the 85 wheel flanges, but slight space is left at 18 and 19 to permit endwise displacement of these tapered elements 7 and 10 in the manner described.

What I claim as my invention is:

1. A railroad track crossing comprising rail sections arranged with their end portions together, where one track crosses another at an angle, instrumentalities comprising movable wheel supporting elements forming with said rails normally closed gaps in each track of said crossing construction for the flanges of the wheels and providing practically continuous wheel tread paths from one side to the other of the crossing for supporting wheels traveling at either angle over the crossing, every movable wheel supporting element in each wheel path being rigidly connected to a similar element in the other path parallel thereto, fixed wheel supports disposed outside and with their inner sides in close juxtaposition to the outer sides of said movable elements, whereby said movable elements are embraced between the flanges of the wheels inside and said fixed wheel supports outside, with sufficient space between the outer side of each movable element and the inner side of each fixed support to permit displacement of said movable elements, and means for shifting said elements whereby said gaps are all normally closed.

2. A structure as specified in claim 1, said instrumentalities comprising two pairs of laterally movable guard bars disposed inside the rails, normally against the inner sides of the rails, said pairs being disposed at an angle to each other, which latter angle is the same as said first mentioned angle, each bar being rigid from one end to the other and extending across from one side of the crossing to the other, with notches in said bars for the flanges of the wheels, and said means comprising springs normally holding all of the guard bars against the inner sides of the rail

sections, the middle portions of said bars normally engaging the inner sides of said movable elements and fixed wheel supports, whereby each movable element projects from its bar into a space between another bar and one of said fixed supports.

3. A structure as specified in claim 1, said instrumentalities comprising two pairs of laterally movable guard bars disposed inside the rails, normally against the inner sides of the rails, said bars being disposed at an angle to each other, which latter angle is the same as said first mentioned angle, each bar being rigid from one end to the other and extending across from one side of the crossing to the other, with notches in said bars for the flanges of the wheels, and said means comprising springs normally holding all of the guard bars against the inner sides of the rail sections, said guard bars having inner tapered integral portions with outer beveled sides, forming said movable wheel supporting elements, and said instrumentalities also comprising stationary blocks forming said fixed wheel supports and having inner beveled faces normally spaced a distance from the beveled outer sides of said tapered portions, providing oblique joints in the tread paths over which the treads of the wheels may roll comparatively smoothly, the middle portions of said bars normally engaging the inner sides of said movable elements and fixed wheel supports, whereby each movable element projects from its bar into a tapered space between another bar and one of said blocks.

4. A structure as specified in claim 1, each said wheel supporting element being movable longitudinally of its allotted wheel tread path.

5. A structure as specified in claim 1, each of said movable wheel supporting elements being movable longitudinally of its allotted wheel tread path thereon, each said movable element being tapered on its outer side from one side of each track toward the other side, with the inner side of each said tapered element straight and in alignment with the inner sides of the rail treads, and four stationary blocks forming said fixed wheel supports and having beveled, and tapered ends co-operating with said tapered elements to provide said wheel tread paths, each block having a straight inner side between its two bevels in fixed alignment with the inner sides of the rails, and each block having an outer side that is longer than its said inner side.

Specification signed this 30th day of October 1928.
